DIRECTIONAL ANTENNA

John H. Gardner, Cambridge, Mass., assignor, by
mesne assignments, to the United States of
America as represented by the Secretary of War

Application March 22, 1945, Serial No. 584,229

11 Claims. (Cl. 250—33.65)

1

This invention relates to antennas for radio object-locating systems and particularly to means for obtaining a radiation pattern closely approximating the relationship $\csc^2\theta$ in one plane where θ is the angle measured from the axis of the radiating means.

In certain airborne radio object-locating systems it is desirable that the antenna afford a distribution of radiant energy in a relatively wide angle such that the variation of energy density versus the radiation angle is a cosecant-squared function, thereby providing relatively constant echo strength for targets located close in or distant. Antennas previously designed for affording such an energy distribution tend to produce upper lobes which cause interference patterns to appear on an indicator scope due to reflections from the belly of the airplane, and have relatively low gain. However, in airborne sets designed for use at medium or low altitudes such as for navigation the primary interest is long range with high gain.

Accordingly, it is one of the objects of the present invention to provide an antenna which is adapted to afford an energy distribution combining high gain with close approximation to a $\csc^2\theta$ beam pattern.

Another object of the invention is to afford a cosecant-squared radiation pattern by the use of a modified paraboloidal antenna.

Another object is to achieve simplicity in the design of an antenna which is reliable and easy to operate.

Still other novel features and advantages will be apparent from the following description of the invention.

In the drawings:

Fig. 1 is an oblique view of an antenna illustrating one embodiment of the present invention;

Fig. 2 is a partly diagrammatic vertical sectional view of the antenna of Fig. 1;

Fig. 3 is a partly diagrammatic view showing the radiation pattern produced by the antenna of the invention.

Fig. 4 is an outline drawing of the reflecting surface of the antenna showing a preferred form thereof.

Referring to Figs. 1 and 2, the radiating element or feed 10, such as a dipole or preferably a double dipole with a pressurizing cup, may be constructed and located in a conventional manner for illuminating a reflector 11. Reflector 11 in the present instance is formed in two parts. The upper portion 12 extending above and below the level of the radiator 10 as viewed in Figs. 1

and 2 is a portion of a paraboloidal surface, which may be termed a dish, having its focal point substantially at the apparent center of radiation of radiating source 10. The lower portion 13 of reflector 11 is a portion of a cylinder disposed with its axis intersecting the axis of the upper portion 12. The spade-shaped cylindrical lower portion 13 has a curvature which is preferably that of a parabola but may, if desired, be that of a hyperbola or ellipse, disposed at a position relative to that of upper portion 12 determined by the radiation pattern desired, as more fully described hereinafter.

The term parabolic cylindrical curvature as employed in this specification has the usual meaning of the curvature of a surface traced by a straight line moving parallel to a fixed line along a parabolic path. A surface of parabolic cylindrical curvature has therefore a focal line 15 defined by the trace of the foci of the parabolic cylindrical surface and a vertex line defined by the trace of the vertices of the parabolic cylindrical surface and an axial plane defined by the focal and vertex lines. The paraboloid 12 and 20 the cylinder 13 are oriented so that the axis of the paraboloid 12 is in the axial plane of the parabolic cylinder 13.

The type of radiation pattern which is produced by this novel antenna is indicated in Fig. 3 and closely approximates the relation $\csc^2\theta$ where θ is the radiation angle measured from the radiation axis $\theta=0$.

Lower portion 13 of the reflector 11 is secured to depend from upper portion 12 in any suitable manner such as by rivets or bolts 13a so that the line of intersection or attachment between upper and lower portions 12 and 13 may be substantially on the line of intersection of the paraboloidal upper portion 12 and a horizontal plane parallel to the axis of paraboloidal portion 12. Preferably, however, the line of intersection follows along a current line in the E plane, that is, on a curved line of intersection of upper portion 12 and a plane through the focal point of upper portion 12 and angularly related to the focal axis of portion 12. While the outer edge of the lower portion 13 contributes relatively little to the radiation pattern, the shape of the cylindrical portion 13 is preferably such that a projection of reflector 11 on a plane perpendicular to its axis is substantially a circle.

This preferred arrangement is shown in the reflector surface outline drawing of Fig. 4 which differs from the Fig. 2 arrangement only in the edge shape of paraboloid 12 where cylinder 13

is attached. This edge is cut as by a plane normal to the plane of the drawing sheet and indicated by a dashed line as passing through the focus of paraboloid 12. It is referred to herein-after as the plane edge of paraboloid 12. In both the Fig. 2 and Fig. 4 arrangements, the axis of dish 12 lies in the axial plane of the parabolic cylinder 13 which plane is the plane of the drawing sheet. Since the radiation from the focal point of paraboloid 12 toward the reflector 11 is 10 plane polarized with the electric vector normal to the drawing sheet, then for the Fig. 4 arrangement, the plane edge of the truncated paraboloid 12 lies in an electric vector plane of the radiation from the feed unit 10.

An important factor is the position of the line of intersection of lower portion 13 with upper portion 12 relative to the reflector and axis, that is the distance D (Fig. 2 and Fig. 4), since the gain is in direct proportion to the distance D and as this determines to a large extent the amount of antenna tilt for which the pattern conforms with a $csc^2\theta$ relation. This tilt, in connection with the maximum range of the system, determines the altitude for which the antenna gives optimum coverage since $h=R \sin \alpha$, where h =height, R =slant range, and α is the angle with the horizon. It has been determined that the distance D is approximately 20% of the diameter of reflector 12. Thus for a reflector having a diameter of 18", the optimum distance D may be chosen as 3.5".

Other important factors in the construction of the reflector according to this invention are phasing of the reflected waves of energy, tilt of lower portion 13 with respect to upper portion 12 and the distance of the center of feed or radiating element 10 from the vertex of paraboloid 12.

For best phasing of the reflected energy it is preferable that there be discontinuity between upper and lower portions 12 and 13 at their line of attachment or intersection. Thus, it is desirable that lower portion 13 be placed slightly behind the upper portion 12 to minimize or avoid the development of "holes" and high lobes on the non- $csc^2\theta$ side of the pattern. It has been found that best results are obtained when lower portion 13 is disposed so that its upper edge is spaced from the rear lower edge portion of upper portion 12, as at 14, Fig. 2, by about $1/40$ of the wavelength in the 3 centimeter band of energy frequencies, or .040" for an 18" reflector as herein described. When this spacing is slightly greater, the radiation pattern is less sensitive to irregularities of the reflector and the feed but this advantage is offset by loss of gain. It should be noted that although the lower portion 13 is spaced behind upper portion 12 the combined reflecting surface or front surface presented toward the radiating element 10, due to the slight overlapping relation thereof, appears as an unbroken surface.

While the tilt of lower portion 13 relative to upper portion 12 is less critical, it is preferable that lower portion 13 be tilted to assume an angle α (Fig. 2 and Fig. 4) about one or two degrees back of a line tangent to the surface of upper portion 12 at 14. That is, the vertex line forms an acute angle α with the axis of paraboloid 12 which is preferably greater than the acute angle β formed by the tangent line. For the 18" reflector referred to above, lower portion 13 would assume an angle α of approximately 75° with a horizontal plane through the axis of reflector 11. A smaller tilt angle (forward from

tangency) has the effect of developing holes and high lobes begin to appear on the $csc^2\theta$ side of the radiation pattern and for tilts more than 3 or 4 degrees back of tangency the energy power distribution at small angles begins to decrease.

It is preferable that the lower portion 13 be parabolic and so dimensioned that its focal length be proportional to that of upper portion 12. It has been determined that the best focal length of lower portion 13 is that which is determined when the focal length of lower section 13 is equal to that of upper portion 12 divided by the sine of the angle between the axes of upper portion 12 and lower portion 13. In the case of an 18" reflector, the focal length is

$$\frac{5.67}{\sin 75^\circ} = 5.86''$$

If the vertex line of the parabolic cylinder lies substantially along a tangent to the paraboloid and if the axial plane of the parabolic cylinder contains the axis of the paraboloid and if the focal length of the parabolic cylinder is equal to that of the paraboloid divided by $\sin \alpha$ it can be proved mathematically that the focal line of the parabolic cylinder will pass through or near the focus of the paraboloid.

For obtaining a good compromise between high gain and good radiation pattern for long range it is preferable that the distance of the center of radiation of feed 10 from the vertex 15 of reflector 11 be shorter than the focal length of the paraboloidal upper portion 12. For the 18" reflector the distance from vertex 15 to the end of the wave guide for a two dipole radiating element is approximately 5.0" for the best compromise.

In airborne antennas of the kind described, it is usual practice to provide a pressurizing cup for maintaining equal pressure around the radiation or feed elements. In certain cases the pressurizing cup has a detrimental effect on the radiation pattern sometimes causing bad holes and increasing the size of unwanted lobes. It has been found that these difficulties may be substantially overcome by providing suitably phased irregularities of the order of one-eighth of the wavelength of the radiant energy on the reflecting surface of the reflector. According to one embodiment of the invention, such irregularities comprise two flat sheet-like members 16 and 17 of conducting material such as brass and preferably of rectangular shape. Members 16 and 17 are mounted substantially symmetrically on opposite edge portions of the upper portion 12 in the E-plane in any suitable manner such as by screws 18. The optimum position of members 16 and 17 at the extremities of reflector 11 in the E-plane is found to be when members 16 and 17 are spaced out from reflector 11 parallel to the axis of the paraboloid about one-sixth of the wavelength in a plane parallel to tangency at the point of attachment with the long dimensions of the rectangularly shaped members 16 and 17 in the H-plane.

It will be appreciated that according to the invention as described above the paraboloidal upper portion 12 tends to direct radiant energy ahead of reflector 11 in a pencil type beam while the lower portion 13 tends to deflect the radiation downwardly. The combination of these effects is such as to produce the $csc^2\theta$ radiation pattern as described, and substantially as illustrated in Fig. 3. With the structure as described the antenna is adapted to afford an

energy distribution pattern, suitable for long range navigation having a relatively high gain such as an absolute gain of the order of 700. It should be noted that certain modifications may be made in the shape of the reflector 11, if desired, to alter the cosecant-squared pattern.

From the above description it will be evident that, in accordance with the present invention, there is provided an antenna structure for transmitting and receiving radio frequency energy waves and preferably waves which are polarized in a chosen plane. The antenna structure is adapted to provide a fan-shaped directional pattern which is characterized in a plane normal to the plane of polarization by an asymmetrical major lobe which corresponds to a cosecant squared energy distribution. The structure comprises a feed element for transmitting plane polarized waves, which element is effectively located at the focus of a reflector. The reflector comprises a first portion having paraboloidal curvature and truncated to provide an edge which lies in a plane cutting the paraboloid at a predetermined distance from the paraboloidal axis. Preferably the plane also cuts the axis of the paraboloid at the focus and is oriented to include the electric vector at the focus. A second portion in the form of a parabolic cylinder is attached to the first portion at the plane edge by overlapping in back thereof and the relative arrangement and dimensions of the two portions are such that the axis of the first lies in the axial plane of the second and the focus of the first lies on or near the focal line of the second.

Preferably in accordance with the invention the overlap of the first and second portions of the reflector is chosen to provide at the plane edge on the reflector surface a discontinuity or step in the electric vector plane of an amount corresponding to $1/40$ of a wavelength of the radio frequency energy waves. Furthermore, the predetermined distance between the paraboloidal axis and the lowest point at which the paraboloid is truncated is chosen to be 20% of the outer diameter of the first portion and the vertex line of the second portion is preferably inclined at an acute angle to the paraboloidal axis which is slightly greater than the acute angle made by a line lying in the axial plane of the second portion and tangent to the paraboloid at the above-mentioned plane edge.

Also in accordance with the invention there is employed a pair of auxiliary reflector surfaces which are symmetrically disposed relative to the axial plane of the parabolic cylinder and located in front of the paraboloidal portion and near the ends of a diameter thereof and spaced from the surface thereof by approximately $1/6$ of a wavelength.

While there has been described certain embodiments of the present invention it will be manifest to those skilled in the art that various changes and modifications may be made therein without departing from the invention.

What is claimed is:

1. A reflector for use with a radiating element for transmitting and receiving radio frequency energy and adapted to provide a fan shaped directional pattern characterized by an asymmetrical major lobe, said reflector comprising a first dish shaped portion having paraboloidal curvature with a vertex and a focus and an axis therebetween and truncated to provide an edge which lies in a plane cutting said dish at a predetermined distance from the paraboloidal axis, and

a second spade shaped portion having parabolic cylindrical curvature with an axial plane defined by the focal line and the vertex line thereof and attached to the first portion at said edge; the relative arrangement of said portions being such that the axis of the first lies in said axial plane of the second.

2. A reflector for use with a radiating element for transmitting and receiving radio frequency energy and adapted to provide a fan shaped directional pattern characterized by an asymmetrical major lobe, said reflector comprising a first dish shaped portion having paraboloidal curvature with a vertex and a focus and an axis therebetween and truncated to provide an edge which lies in a plane cutting said dish at a predetermined distance from the paraboloidal axis and a second spade shaped portion having parabolic cylindrical curvature with an axial plane defined by the focal line and the vertex line thereof and attached to the first portion at said edge by overlapping in back thereof; the relative arrangement of said portions being such that the axis of the first lies in said axial plane of the second.

3. A reflector in accordance with claim 2 in which said overlap is chosen to provide at said edge a discontinuity between the surfaces of said first and second reflector portions of the order of $1/40$ of the wave length of said radio frequency energy, said predetermined distance being chosen to be approximately 20% of the outer diameter of said dish portion and the vertex line of said second portion being inclined at an acute angle to the axis of said first portion which is slightly greater than the acute angle made with the axis of said first portion by a line lying in said axial plane of said second portion and tangent to said first portion at said edge.

4. A reflector in accordance with claim 3 in which a pair of auxiliary reflector surfaces are symmetrically disposed relative to said axial plane of said second portion, in front of said paraboloidal surface, spaced therefrom by approximately $1/6$ of said wave length and located near the ends of a diameter of said paraboloidal surface.

5. A reflector for use with a radiating element for transmitting and receiving radio frequency energy and adapted to provide a fan shaped directional pattern characterized by an asymmetrical major lobe corresponding to a cosecant squared energy distribution, said reflector comprising a first dish shaped portion having paraboloidal curvature with a vertex and a focus and an axis therebetween and truncated to provide an edge which lies in a plane cutting said dish at a predetermined distance from the paraboloidal axis, said plane being parallel to said axis and a second spade shaped portion having parabolic cylindrical curvature with an axial plane defined by the focal line and the vertex line thereof and attached to the first portion at said edge by overlapping in back thereof; the relative arrangement of said portions being such that the axis of the first lies in said axial plane of the second and the focus of the first lies in the focal line of the second.

6. A reflector for use with a radiating element for transmitting and receiving radio frequency energy and adapted to provide a fan shaped directional pattern characterized by an asymmetrical major lobe corresponding to a cosecant square energy distribution, said reflector comprising a first dish shaped portion having paraboloidal curvature with a vertex and a focus and

an axis therebetween and truncated to provide an edge which lies in a plane cutting said dish at a predetermined distance from the paraboloidal axis, said plane also cutting said axis at the focus and a second spade shaped portion having parabolic cylindrical curvature with an axial plane defined by the focal line and the vertex line thereof and attached to the first portion at said edge by overlapping in back thereof; the relative arrangement of said portions being such that the axis of the first lies in said axial plane of the second and the focus of the first lies in the focal line of the second.

7. A reflector in accordance with claim 6 in which said overlap is chosen to provide at said edge a discontinuity or step in the electric vector plane between the surfaces of said first and second reflector portions of the order of $1/40$ of wave length of said radio frequency energy waves, said predetermined distance being chosen to be 20% of the outer diameter of said dish portion, and the vertex line of said second portion being inclined at an acute angle to the axis of said first portion which is slightly greater than the acute angle made with the axis of said first portion by a line lying in said axial plane of said second portion and tangent to said first portion at said edge, and auxiliary reflector means critically located in front of said reflector surface for compensating for irregularities in said directional pattern.

8. A reflector for use with a radiating element for transmitting and receiving radio frequency energy waves polarized in a chosen plane and adapted to provide a fan shaped directional pattern characterized in a plane normal to said polarization plane by an asymmetrical major lobe corresponding to a cosecant square energy distribution, said reflector comprising a first dish shaped portion having paraboloidal curvature with a vertex and a focus and an axis therebetween and truncated to provide an edge which lies in a plane cutting said dish at a distance from the paraboloidal axis, said plane also cutting said axis at the focus and being oriented to cut said dish in the electric vector plane and a second spade shaped portion having parabolic cylindrical curvature with an axial plane defined by the focal line and the vertex line thereof and

attached to the first portion at said edge by overlapping in back thereof; the relative arrangement of said portions being such that the axis of the first lies in said axial plane of the second and the focus of the first lies in the focal line of the second.

9. A reflector in accordance with claim 8 in which said overlap is chosen to provide at said edge a discontinuity or step in the electric vector plane between the surfaces of said first and second reflector portions of the order of $1/40$ of wave length of said radio frequency energy waves, the distance between the axis of said dish-shaped portion and the point in said axial plane at which said dish-shaped portion is truncated being chosen to be 20% of the outer diameter of said dish portion, and the vertex line of said second portion being inclined at an acute angle to said axis of said first portion which is slightly greater than the acute angle made with the axis of said first portion by a line lying in said axial plane of said second portion and tangent to said first portion at said edge.

10. A reflector in accordance with claim 9 in which a pair of auxiliary reflector surfaces are symmetrically disposed relative to said axial plane of said second portion in front of said paraboloidal portion near the ends of a diameter thereof and spaced from the surface thereof by approximately $1/6$ of said wave length.

11. A reflector according to claim 8 in which at least one auxiliary reflecting surface is disposed adjacent one of said first and second portions on the operative side thereof symmetrically with respect to the axial plane of said second portion to provide an irregularity in said one portion.
